3 Claims. (Cl. 242—75)

1

In rolling strips and especially in cold rolling it is for several reasons desired that the strip during the rolling is exposed to a pull either only in the part of the strip leaving the rolling mill or also in the entering part. By this pull the capacity of the rolling mill will be larger but above all a better product is achieved. It is, however, very important that the pull is even and constant and regulable in wide limits.

A regulation of the rolling mill in dependence of the pull in the material can be achieved in a plurality of ways. So may for instance the reels be movable on rails or may be swinging supported, and in both cases actuated by a force tending to pull them in the direction from the mill. The motion of the reel will then be a measure on the pull and can be used for regulating of the pull to a constant value. This arrangement is, however, combined with mechanical disadvantages and the design of it will be complicated and expensive. A pure electrical regulation of the pull by regulation of the driving motors of the reels is also possible but this arrangement will not give a sufficient accuracy during the periods of acceleration and retardation.

The present invention has for its object a method of regulating the pull in the rolling mill, which is simple and not combined with the mentioned disadvantages.

According to the invention the driving aggregate for the reels is supported on the shaft of the reel so that it can perform a swinging motion around it, which motion is counteracted by a stationary member taking up the reactive torque from the driving aggregate. This member may for instance be a spring attached to the foundation, in which the size of the swinging motion will be a direct measure of the torque, but other ways of measuring the torque may also be imagined, for instance a stationary pressure box, containing a member sensitive to the pressure, for instance a resistance or a piezo-electrical crystal, which will give a voltage proportional to the pressure. The principle is that the reactive torque from the driving aggregate is translated to an electric magnitude, which then can be used for the regulation.

If a constant pull in the material is desired, a regulation of the torque exerted on the reel from the driving aggregate will not be sufficient, because the diameter of the reel will change during the rolling operation. When the reel acts on the material coming from the mill exerting a pull in the material, the diameter of

2

the reel will increase when material is wound on it, and if the material is already wound on the reel, it will decrease in diameter when during operation the material is unwound from it. 5 In the latter case, the reel acts as a brake on the material entering the mill. In order to get a constant pull in the material, it is therefore necessary that in the regulation the changes of the diameter of the reel is taken into consideration, i. e. the torque of the driving aggregate must be changed inversely proportional to the diameter of the reel. Thus if M is the torque exerted on the reel from the driving aggregate, the value of

15

$$\frac{M}{r_2} = F$$

must be regulated to a constant value, F being the pull in the material and r_2 the radius of the reel.

According to the invention, the changes of the diameter of the reel can be taken into consideration in two different ways either directly as shown in the arrangement according to Fig. 25 1 or indirectly by means of the excitation current of the motor driving the reel driving aggregate, as shown in Fig. 2.

According to the invention, the voltage impressed on an excitation or regulation winding 30 in a generator exciting the reel driving aggregate motor is made directly proportionally dependent on one hand upon the deflection of the driving aggregate due to variations of the torque exerted by it and on the other hand inversely proportionally dependent upon the diameter of the reel, as stated in the preceding paragraph, the said generator further having a field winding, the control winding, fed with a constant current which can be set to a desired 35 value, and a field winding connected in parallel with its armature.

Such generators are commonly used in many regulating devices and act so that if they are so arranged that their armature currents have 45 an influence upon the voltage impressed upon the regulating field winding over some system to be regulated by the generator, the current from the exciter is changed until the ampere turns of the regulating field winding become 50 equal to the ampere turns of the control winding.

As stated above, Fig. 1 shows an arrangement, in which the reel diameter has an influence upon the regulation by means of a member directly measuring the diameter, whereas Fig. 2 shows an arrangement, in which the reel diameter in-

directly over the field current of the driving aggregate motor has an influence upon the regulation.

In Fig. 1, 1 designates the rolling mill and 2 a pulling reel, which is supposed to be driven by means of a tooth gear 3 supported on the shaft of the reel. This gear is coupled with a driving motor 4 built together with the gear. The gear is balanced by a spring 22 between the gear housing and the foundation. The motor 4 is fed from a generator 5 and the field 7 of the motor 4 is fed in series with a constant voltage current source from a generator 8 having three field windings, of which one is a separately fed control winding 10, one is a regulating winding 11 connected to a potentiometer 12, the contact arm of which being actuated by the driving aggregate and one is a shunt winding 9 connected to the brushes on the armature of the generator 8. The generator 5 as well as the generator 8 is driven by a three phase motor 14. The winding 10 is connected to a potentiometer 6, which in its turn is connected to a constant voltage. By this potentiometer a desired voltage can be impressed upon the winding 10.

The potentiometer 12 is in series with a regulable resistance 13 connected with a constant voltage current source not shown on the drawing. The sliding contact of the resistance 13 is attached to a lever 15 having a roller 16 rolling on the surface of the material wound on the reel 2.

The mill 1 is supposed to be driven by a motor 23 in such a way that the surface speed of the material becomes constant, but any other convenient prime mover may be employed.

The action of the arrangement is most readily described if it first is assumed that the resistance 13 in series with the potentiometer 12 has a constant value. When the diameter of the reel increases, the torque of the driving aggregate has a tendency to increase. The contact arm of the potentiometer 12 will then move upwards, so that the voltage on winding 11 increases and thus the current through it. The alternation of the voltage of the generator 8 will then increase the current through the winding 7. When the current through the winding 7 increases, the armature current of the motor 4 will decrease so that the torque of the aggregate will decrease until the contact arm on potentiometer 12 has moved back to the position giving ampere turns through winding 11 equal to that of winding 10. This is due to the fact that with increasing field current through the motor 4 the induced voltage in it increases and that the armature current must decrease. A given setting of the current through winding 10 means therefore a constant torque from the driving aggregate.

A constant torque means, however, when the diameter of the reel increases a decreasing pull in the material. Now a constant pull is desired and this means that the torque from the driving aggregate must increase with increasing diameter of the reel. This is achieved thereby that the voltage on the potentiometer 12 is caused to vary inversely with the changes of the diameter. This is accomplished by means of the resistance 13 and contact arm 15. When the diameter increases, a larger part of resistance 13 is inserted in series with the potentiometer 12 and thus the smaller becomes the current through the potentiometer 12. A larger diameter of the reel thus means at a given current through the winding 11 correspondent to a given current through the winding 10 a higher position of the contact arm 75

on potentiometer 12 and thus a higher torque from the driving aggregate. As a sum of the whole: The current through the winding 11 is changed proportionally to the torque and inversely proportional to the diameter of the reel and as this current must be constant, the ratio M/d remains constant and thus also the pull.

The arrangement according to Fig. 2 differs from the preceding in that the resistance 13 and lever 15 is dispensed with and instead the winding 11 is fed from a generator 18 excited from a winding 19 in series with the field winding 1, which generator is driven from a motor 17 excited from the potentiometer 12. A motor 23 driving the mill 1 may be connected to the generator 5.

This arrangement acts in the following way: When the reel 2 increases, this on the first hand will cause a decrease of the speed of the motor 4. 20 The torque exerted by it will have a tendency to increase and the gear housing swings, so that a lower voltage is taken out from the potentiometer 12. The motor 17 and thus also the generator 18 will then run with a higher speed and 25 thus its voltage becomes higher and so also the current through the winding 11. As the winding 11 counteracts the windings 9 and 10, the magnetization of the latter being adjustable by a resistance 21, the corresponding alternation of the 30 voltage of the generator 8 then will increase the current through the windings 1 and 9. This increase results in an increased induced voltage in the motor 4 with a corresponding decrease of its armature current and thus of its torque until the 35 gear housing 3 has returned to a position in which the ampere turns of the winding 11 again have been equal to the ampere turns of the winding 10. This position will thus be a function of the position of the gear housing and of the current through 40 the winding 19. An increase of the diameter of the roll will thus result in a corresponding increase of the current through the field winding 1, and as the surface speed of the strip is constant, the said current is inversely proportional 45 to the revolutions of the reel and thus to the diameter of it.

We claim as our invention:

1. In a rolling mill for strips or wires, a driving motor for the mill, a reel for the material to be rolled, a driving aggregate for the reel comprising a gear supported by the shaft of the reel and a motor attached to the gear housing, a member yieldingly opposing the motions of the gear housing under the influence of torque variations in the reel shaft, a generator for the driving aggregate motor having three field windings, of which one is connected in parallel with the armature, one is separately fed from a constant voltage current source and one is fed with a voltage proportional to the deflection of the driving gear and inversely proportional to the diameter of the reel.

2. In a rolling mill for strips or wires, a driving motor for the mill, a reel for the material to be rolled, a driving aggregate for the reel comprising a gear supported by the shaft of the reel and a motor attached to the gear housing, a member yieldingly opposing the motions of the gear housing under the influence of torque variations in the reel shaft, a contact attached to the gear housing sliding over a potentiometer resistance, a regulable resistance inserted in series with said potentiometer resistance, a sliding contact on said regulable resistance attached to a lever in contact with the surface of the material on the reel, a generator having three field windings, of

which one is connected in parallel with the armature, one is separately fed from a regulable voltage source and one is fed from the potentiometer resistance, the armature of said generator in counter-connection to a constant voltage source being connected to the field of the driving aggregate motor.

3. In a rolling mill for strips or wires, a driving motor for the mill, a reel for the material to be rolled, a driving aggregate for the reel comprising a gear supported by the shaft of the reel and a motor attached to the gear housing, a member yielding opposing the motions of the gear housing under the influence of torque variations in the reel shaft, a contact attached to the gear housing sliding over a potentiometer resistance, a motor excited from the said potentiometer, an exciter coupled to the shaft of said motor, a gen-

erator having three field windings, of which one is connected in parallel with the armature, one is separately fed from a regulable voltage source and one is fed from the said exciter, the armature in series with the field winding of said generator and in series with an opposing constant voltage current source being connected to the field winding of the driving aggregate motor.
